United States Patent

Des. 242,001
Patented Oct. 26, 1976

242,001

TABLE

Roland P. Carter, Lynchburg, Va., assignor to The Lane
Company, Inc., Altavista, Va.

Filed Dec. 4, 1974, Ser. No. 529,595

Term of patent 14 years

Int. Cl. D6—03

U.S. Cl. D6—175

Fig. 1.

*Fig. 2.**Fig. 3.**Fig. 4.*FIG. 1 is a perspective view of a table;
 FIG. 2 is a side elevation of the table;

FIG. 3 is a plan view thereof; and

FIG. 4 is an end elevation taken from the left of FIGS. 2 and 3.

The end of the table not shown in FIG. 1 is the same as that shown in FIG. 4.

I claim:

The ornamental design for a table, as shown and described.
